FEED DOG FOR SEWING MACHINES

Jacob Brussell, New York, N. Y., assignor to Isadore Friedman, Roselle, N. J.

Original application July 7, 1937, Serial No. 152,401. Divided and this application September 9, 1938, Serial No. 229,055

6 Claims. (Cl. 112—216)

The present invention is directed to sewing machines, more particularly to multiple needle sewing machines, and the present invention is directed to a new feed dog structure adapted for use in such machines. The present application is a division of my co-pending application Serial No. 152,401, filed July 7, 1937, and entitled "Multiple needle sewing machines".

Although it is highly desirable to have the lines of stitching in shirring as close together as possible, the minimum space between the same has been approximately $\frac{1}{16}$ of an inch due to the limitations of the mechanism which advances the cloth. The feed dog was constructed in the form of a fork with prongs extending in the slots of the throat plate. These prongs were cantilevered, and so had to be of considerable thickness to provide necessary strength. As there must be one such prong as well as a part of the throat between adjacent needles, the needles were spaced a considerable distance apart.

It is among the objects of my invention to overcome the disadvantages of prior machines and to construct the feed dog without prongs by providing a box-like structure, so that the strain on the parts is small and so that the parts extending in the slots in the throat plate may be narrow and the needles may be placed closer together, thus providing for more needles and a finer gauge machine producing a product with lines of shirring closer together than heretofore.

Among the difficulties encountered in increasing the width of the machine and the number of needles has been in keeping the feed dog level. This difficulty arose from the fact that the feed dog rested on and was supported by a small plate which could not be adjusted and which was located midway between the ends of the feed dog. It is among the objects of my invention to construct a feed dog with supports at the ends thereof and to provide adjustable leveling means. I accomplish this by providing at each end of the feed dog an operating part which is attached to the rock shafts of the machine and supplies the motion to the feed dog to advance the cloth and I extend through these parts four screws which abut the under part of the feed dog near its four corners and so providing a leveling means.

In the accompanying drawing, constituting a part hereof, and in which like reference characters indicate like parts,

Fig. 1 is a vertical cross-sectional view taken transversely of the swing machine, showing the feed dog in position for operation; and

Fig. 2 is a fragmentary perspective view of the

feed dog illustrating the unitary character thereof.

The bed 1 of the sewing machine is provided with throat plate 2, of usual construction. Said throat plate in the case of a multiple needle 5 sewing machine, is provided with a series of parallel slots and also with openings for the passage of the needles. The feed dog structure is introduced into said slots for operation.

There is provided a support 3 for the feed dog, 10 said support being U-shaped and having an extension 4 on one side thereof connected to a stud 5 on arm 6, said arm being secured to shaft 7. On the opposite side of said support 3 is a forked end 8 embracing a roller 9, mounted on arm 10, 15 which in turn is secured to shaft 11. Shafts 7 and 11 are given motions such as are well known in the art in order to move the support for the actuation of the feed dog in the usual manner.

The feed dog itself comprises a frame having 20 side members 12 and 13, substantially parallel, and end members 14 also parallel to each other, the four members of the frame constituting a rectangle and usually all the parts thereof are integral. Integral with the frame is provided a 25 series of parallel feed bars 15, having the usual serrated upper surfaces. Said bars project above the frame so that when the feed dog is in position below the throat plate 2, the tops of the extending bars are above the surface of the throat plate and 30 pass through the slots thereof. As bars 15 are rigidly supported at both ends on frame members 12 and 13, they are of extraordinary strength and, therefore, they may be made narrower than was possible in feed dogs heretofore, they may 35 be placed closer together so that more needles may be used in a confined space, thus giving a finer gauge product than was possible in the prior art.

The under part of the feed dog is in the form 40 of an arch 16, so that the feed bars are fixed at the two sides 12 and 13, and gradually taper to about the central portion above the hook 17, which is mounted upon shaft 18 for actuation as usual. The arch 16 has an additional effect in 45 that it allows the placing of the feed dog in close proximity to the hook without interference with the functions thereof.

In the case of a multiple needle machine, and particularly one which has a relatively large 50 number of needles, the feed dog is of relatively great width. Therefore, a problem arises as to the exact alignment and leveling of the feed dog, and the present invention contemplates a device for this purpose. To accomplish this, screws 19 55

are provided in the support 3, at each of the corners of the frame 12—13—14, said screws extending as shown in Fig. 1, so as to contact with the under side of the feed dog frame, which 5 bridges the gap between the upper ends of the legs of the U. The hook shaft lies within the U. There are also provided a series of screws 20 passing through openings 21 at each of the corners of the feed dog frame and being threaded 10 into the support 3.

In order to adjust the level of the feed dog, the screws 20 are loosened and screws 19 are adjusted either upwardly or downwardly, as the case may be, until the frame 12—13—14 is properly leveled. Then the screws 20 are tightened, thereby locking the feed dog in its proper position.

In the prior art, a feed dog was supported from its central point so that it was impossible to properly support a feed dog of any great width. 20 In the present invention, the feed dog frame is supported at a number of points instead of in the center as formerly, and therefore it may be made of any length, still maintaining proper strength for all types of service.

25 Although I have described my invention, setting forth a single embodiment thereof, it is apparent that various modifications and changes in the details of construction are possible within the scope of the invention. For instance, instead of 30 four screws for holding the feed dog in proper position, a lesser or greater number may be, of course, provided. While the feed bars 15 are shown as a single piece with the frame of the feed dog, and I usually prefer to cut the entire 35 feed dog from a single piece of metal, it is, of course, possible to fabricate the same in part and then join the parts to form an integral, rigid structure. In some cases, the adjustability of the feed dog may be omitted. These and other 40 changes in the details may be made without departing from the spirit of the invention, the scope of which is not to be limited except by the character of the claims appended hereto.

What I claim is:

45 1. In a sewing machine, a feed dog comprising a substantially rigid open frame, a plurality of substantially parallel feed bars within said frame, said feed bars bridging the space between opposite sides of said frame, means for adjusting the 50 level of said frame at a plurality of corners thereof, and means for supporting said frame, said adjusting means including screws threaded into

said support and contacting with the corners of said frame.

2. In a sewing machine, a feed dog comprising a substantially rigid open rectangular frame having a pair of substantially parallel sides and a 5 pair of substantially parallel ends, a plurality of substantially parallel feed bars within said frame, said feed bars bridging the space between the opposite sides of said frame and means for supporting said frame.

10 3. In a sewing machine, a feed dog comprising a substantially rigid open rectangular frame having a pair of substantially parallel sides and a pair of substantially parallel ends, a plurality of substantially parallel feed bars within said frame, 15 said feed bars bridging the space between the opposite sides of said frame, a plurality of independent adjusting members adjacent a plurality of corners of said frame for adjusting the level thereof, and means for supporting said frame.

20 4. In a sewing machine, a feed dog comprising a substantially rigid open rectangular frame having a pair of substantially parallel sides and a pair of substantially parallel ends, a plurality of substantially parallel feed bars within said frame, 25 said feed bars being integrally formed with said frame, said feed bars bridging the space between the opposite sides of said frame, and means for supporting said frame.

25 5. In a sewing machine, a feed dog comprising a substantially rigid open rectangular frame having a pair of substantially parallel sides and a pair of substantially parallel ends, the length of the sides being greater than the ends, a hook shaft, the sides being substantially parallel with 30 said hook shaft, a plurality of substantially parallel feed bars within said frame, said feed bars bridging the space between the opposite sides of said frame, and means for supporting said frame.

40 6. In a sewing machine, a feed dog comprising a substantially rigid open rectangular frame having a pair of substantially parallel sides and a pair of substantially parallel ends, a plurality of substantially parallel feed bars within said frame, 45 said feed bars bridging the space between the opposite sides of said frame, and means for supporting said frame including a U-shaped member with means for actuating the same, a hook shaft within said U, said frame bridging the gap between the upper ends of the legs of said U.
